a corporation of Delaware

Application April 25, 1935, Serial No. 18,117
In Germany October 25, 1932

3 Claims. (Cl. 220—15)

My invention relates to refrigerators and it is an object of my invention to provide an improved refrigerator cabinet and cabinet door structure as will appear upon consideration of the following description taken in connection with the accompanying drawings forming a part of this specification and of which:

Fig. 1 is a perspective view of a refrigerator embodying my invention;

Fig. 2 is a detail sectional view taken on line 2—2 in Fig. 1;

Fig. 3 is a front elevation of a member adapted for fabrication of the door of the refrigerator shown in Fig. 1;

Fig. 4 is a front elevation of a member adapted for fabrication of the refrigerator cabinet shown in Fig. 1; and

Fig. 5 is a detail sectional view on lines 5—5 in Figs. 3 and 4.

This application relates back for common subject matter to and is a continuation in part of my application Serial No. 662,651, filed March 25, 1933.

Referring to Fig. 1 of the drawings, a refrigerator cabinet 10 is provided with a door 11 which affords access to a thermally insulated storage compartment 16. An exterior casing for the refrigerator cabinet 10 is provided by a front panel 12, side panels 13 and a top panel 14. The cabinet is provided with a suitable base 15. A closure member 17 affords access to an apparatus compartment in the lower part of the cabinet. The present invention is directed particularly to the structure of the door 11 and the structure of the cabinet around the door opening.

Referring also to Fig. 2 of the drawings, the refrigerator storage compartment 16 is formed by a generally rectangular metal shell or inner casting 18, referred to as a liner. The liner 18 is open at the front and is interiorly coated with porcelain or otherwise suitably treated to form a sanitary lining for the refrigerator storage compartment 16. The liner 18 is surrounded by suitable thermally insulating material 19. The edge of the front panel 12 of the refrigerator is formed with an inturned flange 20 around the door opening of the food storage compartment 16 and is spaced from the forward edge 21 of the liner 18. For the purpose of structurally spacing the edges of the front panel 12 and the liner 18 without transmission of heat by conduction therebetween, and also for the purpose of providing a finished and neat appearing door opening, I provide a novel trim member 22, which may be referred to as a breaker strip. The member 22 is

shown in front elevation in Fig. 4 and is formed of a thin, relatively flat band of a suitable non-absorbent thermally insulating material which may be, for instance, Bakelite. The member 22 is molded as a single piece and in the shape of a substantially flat strip shaped to conform to the door opening as determined by the spaced edges 21 and 20 of the liner 18 and the front panel 12. Both edges of the member 22, or portions thereof are formed with peripherally extending grooves 23. In the present cabinet, the door opening is substantially rectangular and slightly rounded at the corners. The member 22 is slightly enlarged along its edges and the grooves 23 are formed in these enlarged edges 24. The member 22 is placed in the door opening of the cabinet and the edge of the liner is received in the grooves in one edge of the member 22, and the flange 20 on the front panel 12 is received in the grooves in the other edge of the member 20. In fabrication, the member 22 may be first placed in position with its inner edge telescoped over the edge of the liner 18 and the front panel 12 next placed in position with its door opening flange 20 telescoped into the forward edge of the member 22. It will be understood that the edges of the liner and front panel removably extend into the grooves 23 in the strip 22 so that the parts may be disassembled for replacement or repair.

The door 11 comprises an inner metal plate 25, generally referred to as a door pan, and an outer metal wall 26. The door pan 25 is flanged inwardly (toward the door) around its edge. The outer metal wall 26 is turned inwardly over a substantially rectangular wooden frame 27 forming a ledge 28. The edge of the outer plate 26 is also provided with an inturned flange 29. Between the door pan 25 and the outside plate 26 is placed suitable thermally insulating material 30. The flange 29 on the outer plate 26 and the inturned edges of the door pan 25 removably extend into grooves along the edges of a second breaker strip 31 which may be formed of the same material as the breaker strip 22. The parts of the door 11 are secured together by screws 32 extending through the door pan 25 and threaded into the wooden frame 27. The member 31, herein referred to as a second breaker strip, structurally spaces the door pan and outer plate and may be formed by a flat strip of a suitable material such as Bakelite which may be first heated at desired points, corresponding to the corners of the periphery of the door, and then bent at these points into the shape of the door outline as shown in Fig. 3. The ends of the member 31

may be secured together by suitable fastening means such as a block 33 and screws 34. The edges of the member 31 are also slightly enlarged between the points where the strip is bent to form the corners, these enlarged edges containing the grooves which receive the edges of the door pan 25 and the flange 28 on the outer door pan 26. The edges of the member 31 are enlarged inwardly, whereas the edges of the previously described member 22 are enlarged outwardly. Thus, the members 31 and 22 present continuous flat surfaces facing each other around the door opening when the door is closed. When the door is open, the flat surface of the members 22 and 31, unmarred by screws or other visible fastening means, present a neat and finished appearance. It will be understood that the member 31 may be molded or otherwise formed integrally in the same manner as described in connection with the member 22 and that the member 22 may be formed in the manner of the member 31.

What is claimed is:

1. A refrigerator cabinet including a door and comprising wall structure of relatively thin flexible sheet metal plates spaced apart in substantially parallel relation and having corresponding opposed edge portions provided with stiffening flanges extending toward each other in substantially a single plane transversely of said plates, a relatively thin breaker strip in the form of a substantially unitary band disposed edgewise and closing the space between said plates, said strip having grooves in its edges in which said stiffening flanges are removably concealed, the construction and arrangement of the joint between the stiffening flange and breaker strip being such that the stiffening flange and breaker strip reinforce each other against flexure, and screws along the marginal edge portion of said plates spaced from the breaker strip clamping said plates to said breaker strip in said spaced relation, said breaker strip being of sufficient rigidity both to maintain the plates in spaced relation and to withstand the application of force by said screws.

2. A refrigerator cabinet including a door and comprising wall structure of relatively thin flexible sheet metal plates spaced apart and having corresponding opposed edge portions provided with stiffening flanges extending toward each other, a relatively thin breaker strip formed of a plastic in a unitary band disposed edgewise and closing the space between said plates, said stiffening flanges and breaker strip forming a transverse wall, said strip having grooves in its edges in which said stiffening flanges are removably concealed, the construction and arrangement of the joint between the stiffening flange and breaker strip being such that the stiffening flange and breaker strip reinforce each other against flexure, and means independent of said breaker strip and relatively adjacent thereto clamping said plates to said breaker strip in said spaced relation, said breaker strip being of sufficient rigidity both to maintain the plates in spaced relation and to withstand the application of force by said independent fastening means.

3. A refrigerator cabinet including a door and comprising wall structure of relatively thin flexible sheet metal plates spaced apart and having corresponding opposed edge portions provided with stiffening flanges extending toward each other, a relatively thin breaker strip in the form of a unitary band disposed edgewise between said plates and closing the space between the same, said stiffening flanges lying behind at least a portion of the breaker strip so as to be concealed thereby, said stiffening flanges and breaker strip forming a transverse wall, and means adjacent said breaker strip independent thereof clamping said plates to said breaker strip in said spaced relation, the construction and arrangement of the joint between the stiffening flange and the breaker strip being such that the stiffening flange and breaker strip reinforce each other against flexure, said breaker strip being of sufficient rigidity both to maintain the plates in spaced relation and to withstand the compression of said independent fastening means.
